BRUSH HOLDER

Lawrence D. Leach and Leonard G. Strom, Minneapolis, Minn.; said Strom assignor to said Leach

Application May 1, 1944, Serial No. 533,474

3 Claims. (Cl. 171—324)

Our invention relates to removable brush holders for electric motors and has for its object the provision of a simple, strong, and quick-cooling holder of this type.

We are aware that prior to our invention there were numerous brush holders adapted to be inserted into openings in the commutator end of electric motor frames, and we are likewise aware that brush holders of the same general shape and design as the brush holder illustrated in the attached sheet of drawings are old in the art. The object of our invention is to provide a novel frame for such brush holders which, in combination with the "Bakelite" or other plastic material, will provide a greatly reinforced brush holder at a minimum of cost.

Furthermore, we have found in those brush holders made entirely of plastic material or in those holders having disconnected metal inserts embedded in the plastic material, the heat that is generated by frictional engagement of the brush and commutator is not carried away from the base end of the holder; and, as a result of this concentration of heat, the plastic base becomes so hot that it decomposes and chips off. This breaking down, due to undissipated heat, results in the necessity of replacing many brush holders long before the upper part has begun to show the effects of heat and wear.

We have found that by constructing a brush holder with a frame of our novel type and design, that the heat which normally concentrates at the base of the holder is rapidly distributed throughout the other portions of the holder including the body and head portions. As a result of this dissipation of heat the temperature throughout the entire holder is raised considerably but not raised high enough to have a damaging or destructive effect upon the plastic material. At the same time the temperature at the base is lowered below the point of destructibility.

With the above and other objects in view, which will appear as the description proceeds, the invention resides in the combination and arrangement of parts and in the details of construction hereinafter described and claimed. Changes in the precise embodiment of the invention shown can obviously be made without departing from the scope of the invention.

In the accompanying drawing, in which like characters indicate like parts throughout the several views:

Fig. 1 is a top elevation;

Fig. 2 is a side elevation;

Fig. 3 is a vertical axial sectional view taken on the line 3—3 of Fig. 1;

Fig. 4 is a transverse sectional view taken on the line 4—4 of Fig. 2; and

Fig. 5 is a perspective view of the novel frame structure before being embedded into the "Bakelite" or other plastic material, having proper insulating qualities.

Referring more particularly to the drawing, the holder is molded with a flattened body portion 6 having rounded ends 7 and 8. Integrally cast with the plastic body 6 is a collar-like head 9, round in cross section, as shown in Fig. 1.

The base portion 10 of the body is of less width than the diameter of head 9 as shown in Fig. 2. However, at 11 the flattened body portion extends out slightly beyond the peripheral edge of head 9 forming a centrally located shoulder 12 and a flat edge surface 13.

Embedded within the plastic material of the holder is our novel frame which is made up of a notched centrally located supporting leg 14, elongated head and base plates 15 and 16 respectively, and a depending terminal arm 17.

Base plate 16 is provided with a pair of opposed upstanding anchor plates 18 and with a pair of laterally spaced rectangular openings 19. It may be seen by reference to Fig. 5, that the maximum width of supporting leg 14 coincides substantially with the space between the two upstanding supporting anchor plates 18 and the base of leg 14 is soldered or otherwise secured to base plate 16 and anchor plates 18. The upper portion of supporting leg 14 is soldered or otherwise secured to the central portion of head plate 15. Head plate 15 is provided with a pair of laterally spaced round holes 20, the diameter of which openings is slightly greater than the length of the rectangular openings 19 in the base plate 16. Depending terminal arm 17 is provided with enlarged terminal boss 21 through which there extends an opening 22.

Further openings 23 are in the terminal arm. The function of these are the same as the notches in the leg 14, that is to provide more surface for the "Bakelite" or plastic to adhere to, thus imparting greater rigidity to the structure.

It will be observed by reference to Figs. 3 and 5 that the openings 20 in the head plate 15 and the opening 22 in the terminal boss 21 are screw threaded. These holes may be tapped or threaded before the plastic material is molded around the frame, however, it has been found to be best to thread these holes after the application of the plastic to frame member.

As shown in Figs. 3 and 4 the plastic material is so molded as to provide parallel guide passage 23 inter-communicating between the rectangular openings 19 of the base plate 16, and the round openings 20 of the head plate 15. A pair of rectangular carbon members 24, having substantially the same cross section as the holes 19 in the base plate 16, project downward from the base through the openings 19. Embedded in the upper portions of the carbon members 24 are flexible small wire or cable members 25 which extend out the upper ends and connect to contact plates 26. A pair of coil springs 27 are interposed between the contact plates 26 and the carbon members 24 and the upper portions of carbon members being reduced to provide a shoulder for the coil springs 27.

Screw 28 is shown as being threaded into terminal boss 21.

Plastic covered metallic closures 29 are shown as having screw threaded engagement with apertures 20 in the head plate 15. Plastic head 9 is provided with diametrically opposed openings 30 thru which may be extended, screws or threaded bolts, for the purpose of securing the holder in position in the motor frame.

Coil springs 27 are of a length greater than the axial length of the parallel guide passages 23 and therefore they exert a constant, but gentle downward or outward pressure against the carbon members 24 thus keeping carbon members 24 in contact with the commutator of the electric motors in which they are placed, until said carbon members have been reduced in length by such wear to a point where they must be replaced.

This replacement is accomplished merely by the unscrewing of closure members 29 withdrawing the assembled contact plate, coil spring and carbon member and replacing same.

The electricity picked up by the brush or carbon member 24 runs up the electric wire or cable member 25 to contact plate 26, thence to metallic closure 29, to head plate 15 down terminal arm 23 to terminal boss 21 and out to point of storage or consumption through electric wire or the like attached to screw 28.

The electrical circuit, above described, is the only circuit possible in brush holders not having a connected metal frame. However, with our device there are several alternative and supplementing circuits for the electricity picked up by the carbon brush members. For instance, all the electricity picked up by the brush must necessarily be discharged through the base member 16 and up through the central supporting leg 14 to head plate 15 and thence down through the terminal arm 17. This is true because carbon members 24, when in contact with the commutator, are always in tight frictional engagement with rectangular openings 19 through which they pass.

While it is understood that our novel frame member can be made of any metal which is a

good conductor of electricity and heat, we have found in practice that brass is very satisfactory for this purpose.

What we claim is:

1. In a monolithic brush holder molded from insulating material and comprising a flattened body portion and an enlarged head—a metallic frame member consisting of a supporting leg, a base plate, a head plate, and a terminal arm, said base plate having laterally spaced rectangular openings, said head plate having laterally spaced circular openings aligned with the openings in the base plate, said supporting leg being secured at the base and head plates intermediate the spaced openings, said molded body portion having laterally spaced parallel guide passages, inter-communicating between the aligned openings in the head and base plates, and said terminal arm being secured to and depending from the head plate and terminating in a screw threaded boss, the outer surface of said boss being flush with the side surface of the molded body portion.

2. In a monolithic brush holder molded from insulating material and comprising a flattened body portion and an enlarged head—a metallic frame member consisting of a supporting leg, a base plate, a head plate, and a terminal arm, said base plate having laterally spaced rectangular openings, said head plate having laterally spaced circular openings aligned with the openings in the base plate, said supporting leg being secured at the base and head plates intermediate the spaced openings, said molded body portion having laterally spaced parallel guide passages, inter-communicating between the aligned openings in the head and base plates, said base plate being provided with a pair of centrally located laterally spaced upstanding anchor flanges embracing the base end of the supporting leg, the lower surface of said base plate constituting the base end surface of said holder, and the outer faces of said anchor flanges being exposed on the flat sides of the body portion.

3. In a monolithic brush holder molded from insulating material and comprising a flattened body portion and an enlarged head—a metallic frame member consisting of a supporting leg, a base plate, a head plate, and a terminal arm, said base plate having laterally spaced rectangular openings, said head plate having laterally spaced circular openings aligned with the openings in the base plate, said supporting leg being secured at the base and head plates intermediate the spaced openings, said molded body portion having laterally spaced parallel guide passages, inter-communicating between the aligned openings in the head and base plates, said supporting leg being notched on its edges, and said terminal arm being provided with a plurality of plastic receiving apertures.
